United States Patent Office

Des. 183,720
Patented Oct. 21, 1958

183,720 *

EXPANDED METAL SHEET OR SIMILAR ARTICLE

Dallas S. Casley, Belpre, Ohio, assignor to Penn Metal Company, Inc., Boston, Mass., a corporation of Delaware

Application January 6, 1958, Serial No. 49,141

Term of patent 14 years

(Cl. D54—2)

FIG. 1

FIG. 2

Fig. 1 is a top plan view of a complete repeat unit of my new design for an expanded metal sheet;

Fig. 2 is an enlarged section taken on the lines 2—2 of Fig. 1.

I claim:

The ornamental design for an expanded metal sheet or similar article, substantially as shown.
